ATTORNEY

UNITED STATES PATENT OFFICE

WILLIAM A. FONKEN, OF SEATTLE, WASHINGTON

METHOD OF AND APPARATUS FOR PARING FRUIT

Application filed January 20, 1927. Serial No. 162,278.

This invention relates generally to the fruit canning art, and particularly to a device for paring pears.

The first object of this invention is to construct a pear paring machine whereby pears may be quickly and efficiently pared in order that oxidation may be reduced to the minimum and that the pared fruit may remain as near as possible to their original condition, namely that the portions of the pear which would normally be worn off by handling would, by the use of this machine, remain sharp and the entire surface of the pear maintain its original light color.

15 The second object is to reduce the amount of waste ordinarily attending fruit paring operations and to increase the quality of the output by making every individual piece canned identical in size and shape with every other piece in the same can.

20 The third object is to provide a special form of holding means whereby the plain surface of a sliced pear is first held by suction against a face plate while being pared and then expelled by pressure to make room for the next pear to be pared.

25 These, and other objects, will become more apparent from the specification following as illustrated in the accompanying drawing, in which:

30 Figure 1 is a vertical section through the device showing a representative form of mechanism whereby the above-named objects can be accomplished. Figure 2 is a vertical section through the face plate for holding the fruit showing the paring operation being performed. Figure 3 is a plan of the face plate showing the relation of the paring knife to the face plate itself.

35 40 Similar numbers of reference refer to similar parts throughout the several views.

45 Referring in detail to the drawing, in order to illustrate the method and apparatus there is shown a face plate 10 which is somewhat pear-shaped and is provided with a plurality of countersunk holes 11 which communicate with the interior of the body 12 to which the face plate 10 is attached by means of the screws 13.

50 The body is screwed onto a pipe 14 in

which are the T's 15 and 16. The T 15 is joined by a pipe 17 to the suction side of a pump (not shown). The pipe 17 includes a valve 18 whose operating lever 19 is urged toward a closed position by the spring 20. 55 The T 16 is connected by the pipe 21 to the pressure side of the pump (not shown). The pipe 21 includes a valve 22 whose operating lever 23 is urged toward a closed position by means of a spring 24.

60 In the frame 25 is mounted a rock shaft 26 on one end of which is mounted a knife 27 which is secured to the shaft by means of the screws 28. The knife 27 fits rather closely to the outer edge of the face plate 10. 65

On the shaft 26 is secured a pinion 29 which meshes with a rack 30 which is slidably moved by the connecting rod 31 on the worm wheel 32 which is driven from a worm 33 by any convenient power. On the shaft 70 26 is a suction applying cam 34 which engages a roller 35 on the plunger 36 whose end engages the lever 19. On the shaft 26 is also a pressure applying cam 37 which engages a roller 38 on the plunger 39 whose 75 end engages the lever 23.

The operation of the device is as follows. 80 Pears are first graded for size and sliced longitudinally through the center into halves. A half pear is then placed with its cut side 85 against the face plate 10. The rotation of the worm 33 causes the cam 34 to open the valve 18 which produces a suction within the body 12 and holds the half pear firmly against the plate 10.

85 The knife 27 now starts its travel around the half pear just underneath its skin 40, completely removing same at one half revolution of the shaft 26. Pressure is now admitted to the body 12 causing the pared half 90 pear to be removed from the face plate while the knife 27 is being restored to its original position. Obviously, the knife 27 can be two edged so that at one operation 95 it pares from one side and at the next operation it pares from the other side, without departing from the spirit of this invention.

While in actual operation a machine for performing the work above described might 100 embody many auxiliary parts to render com-

mercial the use of the method and apparatus, only a sufficient number are herein illustrated to show its working principle.

I am aware that many forms of fruit paring and holding devices have been constructed in the past; I therefore do not claim such devices broadly, but I do intend to cover all such forms and modifications thereof as fall fairly within the appended claims.

10 I claim:

1. A method of paring fruit consisting of progressively cutting the fruit to form a plane surface thereon; then holding the fruit by suction against said plane surface; and then paring the exposed skin from said fruit.

15 2. A method of paring fruit consisting of progressively cutting the fruit to form a plane surface thereon; then holding the fruit by suction against said plane surface; then paring the exposed skin from said fruit; and then exerting pressure against the flattened side of said fruit for the purpose of releasing same from its holding means.

20 3. A method of paring fruit consisting of first halving said fruit; then holding same by suction against its flattened surface in a manner that its skin shall be exposed and its edges shall slightly overhang its supporting surface; and then paring said fruit by 25 means of a curved motion coaxial with said fruit in a movement starting and terminating below its supporting surface.

35 4. A paring machine having a perforated face plate shaped similar to a cross section of the fruit to be pared and slightly smaller than said cross section, said plate having means for exhausting air from between said plate and fruit; and a curved knife rotatably mounted coaxial with said fruit supporting plate.

40 5. A paring machine having a flat perforated fruit engaging plate slightly smaller than the cross section of the fruit to be pared; means for exhausting air from between said plate and fruit placed thereon; a knife for paring said fruit while held on said plate; and means for forcing air between said fruit and plate.

50 6. A paring machine having a pear-shaped flat face plate; a supporting cup under said plate, said plate having holes therein communicating with said cup; means for exhausting air from said cup; means for injecting air into said cup; and a rotatable 55 knife for paring half fruit while its flat side is held against said face plate by suction within said cup.

60 7. A method of paring fruit consisting of progressively cutting the fruit to form a plane surface thereon; then holding the fruit against said plane surface with its entire skin surface free; and then paring the skin from said fruit.

65 8. A method of preparing fruit for canning consisting of progressively cutting the

fruit to form a plane surface thereon; then holding said fruit while leaving its entire skin surface free; and then removing the outer portion of said fruit while so holding the fruit.

70 9. The method of paring a pear which consists in splitting the pear, then holding the split pieces in such fashion as to leave the entire skin surface free of the holding means, and paring the skin from the split 75 piece by a single stroke of a cutting tool.
